UNITED STATES PATENT OFFICE.

HENRY J. G. RUDOLF, OF NEW YORK, N. Y., ASSIGNOR TO VALVELESS OIL BURNER CORPORATION, OF NEW YORK, N. Y., A CORPORATION OF NEW YORK.

OIL-BURNING FURNACE.

Application filed June 14, 1923. Serial No. 645,418.

The present invention relates to means for generating heat by combustion of oil fuel, and has for its main objects to secure the most complete and most efficient possible combustion of the fuel, to prevent and eliminate deposition of carbon of any sort, whether the hard and refractory variety or the soft and sooty kinds, or any others; and to carry on the combustion with the minimum of noise.

The invention consists in the means which I have devised and used successfully and satisfactorily to accomplish these objects and in all equivalents thereof which embody the same principles. I will now explain the principles and fundamental characteristics of the invention in connection with a specific embodiment thereof which I have designed and used with a domestic steam heating boiler.

In the drawings,—

Figure 1 is a sectional view showing in an illustrative manner the essential characteristics of the species of the invention above referred to as applied to such a boiler.

Figure 2 is a plan view of the furnace on a larger scale.

Figure 3 is a perspective view of that portion of the furnace which I have called the "combustion pot."

Like reference characters designate the same parts wherever they occur in all the figures.

In these drawings I have not attempted to show all the structural details which may be desirable or necessary in commercial practice for combining the furnace with its combustion pot and boiler, as such details do not affect the actual invention and are within the scope of the expedients known to those acquainted with the art and available for all practical purposes. What I have aimed to do by these drawings and the following description, is to explain the principles and essential characteristics of the invention in such a full and exact manner that those skilled in the art may apply such principles, possibly in many specifically diverse forms, to the conditions of various particular problems.

With this explanation it will be understood that 10 represents in a conventional manner a typical fire pot or furnace, and that 11 typifies any steam boiler or water heater, or other thing which it is desired

to heat by the combustion of fuel. While the illustration may represent the boiler of a domestic heating plant, in principle it typifies anything which may be heated. 12 represents the front wall of the furnace and 13 represents the burner which comprises essentially an external tube for air and an internal tube or nozzle 14 to which oil is delivered. Here again the showing is illustrative and typical, and the burner so shown may typify any atomizing or spraying means which is adapted to furnish a mixture of finely divided liquid fuel, and air to support combustion. It is not vital to the invention here claimed that the air supply should be delivered so as to surround and envelop the fuel; for other or reverse arrangements of air and fuel are possible. What is important from the present standpoint is that the fuel and air are delivered together into the furnace, or fuel is so delivered in a more or less finely divided condition, and the air is delivered under such pressure that it issues from the burner with a considerable velocity.

As oil is the fuel which this furnace is particularly intended to burn, I will from now on refer to the fuel as "oil"; and within the meaning of this term I include crude petroleum, kerosene, so-called furnace oil, fuel oil, and any other mineral, animal or vegetable oils which may be burned with the aid of this apparatus.

The burner opens into a structure 15 which projects into the furnace enclosure from the front wall 12 and which, for convenience of description, I call a "combustion pot," not meaning to imply by the use of that name any limitation in the protection which I claim. This so-called combustion pot at its forward end surrounds the burner and the combustible mixture issuing therefrom, but at its rear end only partially surrounds the mixture and the products of combustion thereof. Thus the pot has a roof or top wall 16, side walls 17 and a bottom wall 18, the latter being relatively short and enclosing only the forward part of the pot. The front end of the pot is preferably closed by a front wall except for the opening or passage through which the burner extends, in order to exclude excess air, since it is intended that the quantity of air supplied through the burner itself shall be enough to effect complete combustion of the fuel. Modification in this respect, however,

is possible and I may, in some instances, provide openings, with or without controlling dampers, external to the burner in such front wall.

5 The burner is directed upwardly toward the roof or top wall 16 of the combustion pot at such an angle and from such a location in the forward end of the combustion pot, that the oil issuing from the oil nozzle thereof is thrown against said top wall, and the air issuing from the burner is also caused to impinge upon and flow over such top wall toward the rear.

This combustion pot is preferably made 15 of material having considerable heat-conducting capacity, as metal. It is conveniently made of cast iron, though other materials and modes of construction may be employed. The top wall in particular is 20 made thin enough and with such capacity for conducting away heat that it will not be excessively heated by the impinging flame and preferably not above the temperature of dull red heat. Radiating ribs 19 may be 25 provided, if necessary, on the outside of the top wall to assist in more rapidly dissipating the heat imparted by the flame. Wide variations in the form and dimensions of 30 this top wall are possible according to the particular conditions of use, the quantity of oil and air supplied, the pressure of the air supplied, etc., it being important to cause the oil delivered from the burner and not yet ignited to be spread over the top 35 wall and swept from the same by the air current, and at the same time to be heated by the flame, but not to be heated to so high a temperature as will cause cracking of the oil with deposition of hard carbon.

40 It is known that formation and deposition of hard carbon in oil furnaces is due to cracking of the oil by intense heat before combustion has taken place; and I have discovered that by causing the oil to impinge 45 on a heated surface, the temperature of which is kept below the degree at which oil will be so decomposed as to liberate solid carbon, I am able to effect not only heating of the oil, but also to divide it into small 50 particles and cause thorough mingling with air as well as to prevent it from reaching the rear wall of the furnace in the form of large drops.

The side walls 17 of the combustion pot 55 perform the useful function of confining the burning mixture within the limits of the top wall until it leaves the rear edge of the latter, and thus of preventing escape laterally of large drops of oil, which might 60 lodge on the side walls of the furnace or fall to the floor before being wholly consumed.

The bottom wall 18 of the combustion pot 65 confines the fuel mixture at its entrance into the furnace and during the initial stages of combustion, but the short extent of this wall

and the open formation of the combustion pot at the bottom in rear of the wall allows the air and products of combustion to expand freely and gradually as their temperature rises, thus avoiding the noise which is 70 due to sudden expansion of hot gas under pressure due to heat generation while in confinement.

At a considerable distance toward the 75 rear of the furnace, the exact distance being a matter determined by the amount of fuel being burned and the pressure at which air is supplied, I have arranged a baffle 20 made of suitable refractory material, preferably fire-brick. In front of the baffle is 80 a platform 21 and at each side or end of the latter are wings 22 between which and the baffle, and on the platform, is placed a body of sand 23 or equivalent porous, absorptive and incombustible material. The function 85 of the baffle, of course, is to arrest the streaming flames and direct them upwardly; while that of the sand is to receive, absorb and evaporate any particles of burning oil which may travel so far before being consumed. When unburned oil impinges on a solid wall, arranged in the manner of a baffle or bridge wall, in a furnace, deposition of light fluffy carbon or soot occurs, 90 this being due to the formation at that point of a gas pocket which prevents access of enough air to complete the combustion of oil or to burn off the carbon.

I have found that by providing sand in 95 a position to catch all of the unburned oil which is carried to the baffle, such oil is at once soaked up before it can be burned to the condition of carbon, and that the heat of the flame evaporates the oil so absorbed. Such oil being thus converted into true 100 vapor rises through and with the flame until it is completely burned. The vapor so produced does not lodge on the baffle or leave 105 deposits of carbon. Instead of sand I may use for the purpose last described any other material which is sufficiently absorptive and refractory to accomplish results the same in kind.

It will now be understood that as oil and air are blown into the furnace, the oil is 110 partially converted into spray by the action of the air alone, but that most of the oil strikes the top wall of the combustion pot and is there spread out into a thin film. The air flowing over this wall sweeps the oil 115 to the rear edge of the wall and there breaks it into spray. It is to be understood that after the fire is once lighted, combustion begins immediately after the oil leaves its nozzle, wherefore there is flame as well as unburned oil and air in the combustion pot. The flame, of course, heats the roof of the 120 pot and causes much of the oil to be vaporized before it is swept from the rear of the pot.

I am able by the aid of this pot and for the reasons set forth to obtain a good hot fire without the roaring noise which is an objectionable feature of many oil burners, and without deposition of carbon. The stream issuing from the combustion pot is mostly oil vapor, air, and the products of combustion, but may contain a small remnant of liquid oil in small drops. Such drops as are not wholly burned after reaching the baffle lodge in the absorptive body 23 and are there vaporized, and subsequently burned also without deposition of carbon. Thus I have succeeded in burning oil with complete combustion, without deposition of carbon, and without appreciable noise.

As many burners and combustion chambers may be provided in the same furnace as desired. In Figure 2 I have shown two of them, and have illustrated therein the combination in which one is smaller than the other and is usually maintained in constant operation so as to furnish a constant minimum of heat and serve as a pilot for igniting the other burner or burners when provision is made for the full amount of heat. The reference characters used in Figure 2 designate the main burner and combustion pot, while the same characters, modified by exponents, designate the pilot burner and its combustion pot. In addition to the parts already described, however, I have shown here a communicating passage 24 from one pot to the other for the purpose of transmitting flame from the pilot burner to light the main burner when oil is turned on to the latter.

So far as the burner and the combustion pot here described are applicable to burning liquid fuels other than those coming within the specific definition of oils, I claim the same within the scope of the present invention, and without limitation to any spe-

cific use or environment, or in connection with any specific fuel.

What I claim and desire to secure by Letters Patent is:

1. In a furnace, a combustion pot and means for delivering liquid fuel and air into the forward end thereof, said combustion pot having a top wall against which the inflowing fuel is caused to impinge and having side walls to limit the lateral dispersion of fuel and air and being open at the rear, and at the rear portion of its under side, to permit free expansion of the hot products of combustion and heated air.

2. In a furnace, the combination of a combustion pot having top and side walls and a bottom wall which extends part way only of the distance from front to rear, said pot being open at its rear and at the rear portion of its bottom, with a burner having oil and air passages entering the front of the combustion pot and arranged to cause impingement of the delivered oil and air against said top wall.

3. In a furnace, the combination of a combustion pot having top and side walls and a bottom wall which extends part way only of the distance from front to rear, said pot being open at its rear and at the rear portion of its bottom, with a burner having oil and air passages entering the front of the combustion pot and arranged to cause impingement of the delivered oil and air against said top wall, and a baffle located at the rear of said combustion pot in position to be impinged upon by the flame issuing from the latter and including a mass of absorptive refractory material adapted to absorb particles of unburned oil in the flame.

In testimony whereof I have affixed my signature.

HENRY J. G. RUDOLF.
